INJECTOR AND BLADE DISPOSAL
DEVICE FOR RAZORS

Joseph C. Fennelly, Ross, Calif., assignor, by
mesne assignments, of one-half to H. Struve
Hensel, New York, N. Y.

Application October 13, 1949, Serial No. 121,175

6 Claims. (Cl. 30—40)

1

This invention relates to improvements in an injector and blade removing device for injector type razors and refers more particularly to the hook or gripping attachment by which used blades are withdrawn from the razor into a disposal compartment of the injector housing.

This application is a continuation-in-part of a previous application Serial No. 714,722, filed December 7, 1946, now Patent No. 2,608,755.

An injector containing a magazine of new blades has heretofore been employed to change the blade of a razor by affixing the injector to the head and reciprocating a slide in the injector simultaneously ejecting the old blade by introduction of a new unused blade, the disposal of the rejected blade requiring manual handling.

In my prior application there was disclosed an injector for this type of razor having a magazine compartment and a blade disposal compartment with a slide for introducing the new blade and a hook arrangement for extracting the used blades. The injector-extractor there disclosed was operably attached to the head of the razor in the conventional manner, that is, by inserting a wedge between the guard portion and top blade holding portion of the head.

The novelty in the instant invention lies principally in the design of the extractor hook, the use of springs on top of the magazine to assure positive operation of the extractor and the use of a lateral wedge to keep the blade in a proper position in the razor head so it may be engaged by the extractor attachment.

An object, therefore, of the invention is to provide an injector-extractor for razors having magazine and blade disposal compartments with a slide equipped with an extractor attachment and a depressing element on the extractor for automatically holding it in an inoperable position during the injection of the blade into the razor.

Another object is to provide an injector-extractor mechanism with magazine and blade disposal compartments and a magazine equipped with depressing springs which assure more positive operation during the blade extraction.

A further object is to provide an injection and extraction device utilizing a wedge for attachment to the razor head, said wedge equipped with means for laterally moving the blade in the razor head upon insertion of the wedge so the extraction member of the slide readily engages the blade.

Other and further objects will appear from the description which follows.

2

In the accompanying drawings which form a part of the specification and are to be read in conjunction therewith and in which like reference numerals indicate like parts in the various views,

Fig. 1 is a perspective side view of a blade injector-extractor mechanism embodying the invention.

Fig. 2 is an enlarged side sectional view of the injector-extractor shown attached to the head of the razor with a blade withdrawn from the razor and about to be deposited in the disposal compartment,

Fig. 3 is a sectional view taken along the line 15 3—3 in Fig. 2 in the direction of the arrows,

Fig. 4 is a view similar to Fig. 2 with the injector-extractor slide advanced from its retracted position to move the bottom blade from the magazine compartment into the head of the 20 razor.

Fig. 5 is a similar view to Fig. 4 with the slide advanced to its extreme forward position where the new blade is lodged in the head of the razor,

Fig. 6 is a view such as that shown in Fig. 5 25 with the extractor hook in engagement with an aperture in the blade at the beginning of the extraction operation,

Fig. 7 is a like view showing the manner of 30 withdrawing the blade from the razor head by retraction of the slide and depicts the intermediate operation between Fig. 6 and Fig. 2,

Fig. 8 is a perspective detail of the blade holding magazine, and

Fig. 9 is a detail of the slide mechanism.

35 Referring to the drawings, and particularly Figs. 2 and 4 there is shown diagrammatically, a razor of the injector type, the head of the razor designated by the numeral 10 and the handle by the numeral 11. The injector-extractor shown 40 attached to the razor head in the various views consists of a housing 12 divided centrally into an upper magazine compartment 12a and a lower blade disposal compartment 12b. From the forward end of the housing and at one edge extends 45 a wedge 13. This wedge is adapted to be inserted between the guard and blade holding portions of the razor head when the injector-extractor is put to use to inject or eject a blade. At the rear of the housing is removably fitted a closure 12c 50 hinged on a pin 14 in the lower portion and secured by means of a pin 14a in the upper portion. This provision for opening the rear of the blade may be eliminated, if desired.

The sides of the housing are slotted as shown 55 at 15 and in these slots is reciprocated a slide 16

shown disassembled from the housing in Fig. 9. Attached to the sides of the slide on the outside of the housing are knobs, handles or wings such as the triangular shaped members 16a shown best in Figs. 1 and 9 for moving the slide back and forth. The base or floor portion of the slide has a raised portion in the form of an inverted trough 16b, the forward end abutting the rear end of the lower blade of the magazine during the injection operation. Pivoted as by a rivet 17 to the under side of the slide in the inverted trough 16b is a flexible extractor 18. Beneath and at the free end of the extractor is a hook 18a and on top of the extractor and above the hook are cams or depressing elements 18b.

The magazine for the blades, probably best shown in Fig. 8, is a container 19 whose front end wall 19a has a lower slot-like opening near its bottom to permit transfer of blades from the magazine to the razor and a top 19b having a front extension 19c and a doubled back tongue or tail plate extension 19d. The blade magazine 19 is limited in its downward movement at the forward end by abutment of extension 19c with the stop or shoulder member 20 affixed to the inside forward wall of the upper compartment 12a of the housing.

Tongue 19d fits in a slot in the end closure 12c of the housing and serves as a pivot for the magazine as it moves during the injection and extraction of the blades as shown in Figs. 5, 6 and 7. Above the magazine and between its top and the top of the housing is placed a strip spring 21 which imposes constant downward pressure on the magazine and keeps it properly located within the housing for the discharge of new blades from the magazine to the razor and withdrawal of used blades from the razor to the disposal compartment 12b. Within the magazine are shown the new unused blades 23 held under spring pressure against the bottom by a strip spring 22. These blades have a small perforation or slot 23a near the rear ends and sharpened edges. The perforations or apertures are positioned to be engaged by the hook portion 18a prior to removal of the blade from the razor as hereinafter described.

Formed in the top edge of the wedge or key 13 by which the injector-extractor housing is attached to the razor is a tongue or cam plate, 50 13a. This tongue contacts the rear edge of the blade in the head and moves the blade forwardly to assure engagement of hook 18a with aperture 23a in the blade.

In operation a stack of new and unused blades are supplied to the magazine and the magazine inserted in the upper compartment of housing 12. The rear closure 12c is applied to the housing and slide 16 retracted to a position shown in Fig. 2. The wedge 13 is then inserted into the head 10 of the razor and the slide is advanced until the inverted trough portion 16b abuts the rear end of the lower blade in the magazine. At this time the camming surface or depressing elements 18b on top of the extractor contact the lower surface of the blade and keep the hook 18a depressed in an inoperable position as shown in Fig. 4. Continued advancement of the slide as indicated in Fig. 4 feeds the blade from the magazine into the head of the 70 razor until the slide reaches the position shown in Fig. 5 where the extractor hook is still depressed beneath the new blade. The housing is then removed from the razor and the razor is ready for use.

When it is desired to remove a used blade from the razor, wedge 13 is again inserted into the razor head and with the slide in its forward position, as shown in Fig. 6, the extractor hook will 5 assume a raised position since cams 18b are outside of the housing and free of the depressing influence of the blades in the magazine. Hook 18a will now ride over the top of the blade in the razor head and engage aperture 23a in the 10 manner shown in Fig. 6. The sequence of the extraction operations starting with Fig. 6 is continued in the showing in Fig. 7 at which time the blade is partially withdrawn from the razor. Note that as the slide is retracted cam members 18b contact the bottom of the new blades 15 lifting the front end of the magazine to permit easy access of the used blade into the disposal compartment. Continued retraction of the slide brings the used blade into a position shown in Fig. 2 when the slide is completely retracted and the used blade has been withdrawn completely 20 into the disposal compartment of the housing. Forward movement of the slide from the position shown in Fig. 2 will disengage the used blade from the extractor hook and deposit the blade in the disposal compartment as shown in Fig. 4. This sequence of operations may be performed in injecting and extracting blades from the razor until the magazine of new blades has 25 been exhausted. When the new blade magazine has been exhausted and the used blades deposited in the disposal compartment the housing may be replaced with a new injector-extractor containing a magazine of new blades.

35 Thus, it will be seen that there has been devised an improved type of injector-extractor magazine by which there may be positively injected a new blade into the head of a razor and an old blade withdrawn into a disposal compartment without manual handling of the individual blades during extraction of the blade from the razor head or subsequent disposal of the used blade. The design of the extractor hook, the depressing cams which hold the hook in an inoperable position while the blade is inserted in the razor and the spring mechanism above the magazine for imposing a constant downward pressure thereupon serve to effect more positive operation of the extractor. The lateral cam or wedge mechanism 13a which moves the blade forwardly in the head, likewise operates to assure engagement of the extractor hook with the blade aperture.

40 From the foregoing it will be seen that the invention is well adapted to attain the ends and objects hereinbefore set forth together with such other advantages which are obvious and which are inherent to the structure. As many possible embodiments may be made of the invention without departing from the scope thereof it is understood that all matter herein set forth or shown in the drawings is to be interpreted as illustrative and not in a limiting sense.

45 It should also be understood that certain features and subcombinations are of utility and may be employed without reference to other features and subcombinations. This is contemplated by and is within the scope of the claims.

50 Having thus described my invention, I claim:
 1. An injector and blade removing device for an injector type razor comprising a housing with a razor head attaching key by which the housing is operably associated with the razor head, magazine and blade disposal compartments in the 55 housing communicating with the blade receiv-

ing portion of the razor head through a slot in the end of the housing adjacent the razor head, blade holding means within said magazine compartment adapted to support a stack of new blades, yieldable means cooperating with said blade holding means to maintain the lowermost blade in said stack in substantial alignment with said slot, a slide between said magazine and blade disposal compartments and movable longitudinally thereof, an extractor member operable with said slide for removing a blade from the razor head through said slot into the housing upon movement of the slide in one direction, said extractor member having associated therewith a camming element adapted to displace the stack of new blades laterally of said slot to permit entry of the used blade therethrough and into the blade disposal compartment upon said movement of the slide, and an injector member on the slide for discharging the lowermost blade on said stack from the magazine into the razor upon movement of the slide in the opposite direction.

2. In a device for injecting and removing blades from an injector type razor, a housing having an attaching key for mounting it in operative position with respect to the razor head and provided with an opening therein aligned with and adjacent the blade receiving portion of the razor head, a blade supporting member for supporting a stack of new blades within said housing, said member being normally disposed longitudinally of the housing in substantial alignment with said opening and dividing said housing into an upper blade storage compartment and a lower blade disposal compartment, said member being swingably mounted to permit upward movement of that end of the member adjacent said opening, a slide between said blade storage compartment and said blade disposal compartment and movable longitudinally thereof, an extractor member operable with said slide for removing a blade from the razor head upon movement of the slide in one direction, said extractor having associated therewith a camming element adapted to lift the free end of said blade supporting member above the level of said opening thereby to permit free entry of the blade into

the blade disposal compartment during said movement, and an injector member on the slide for discharging a new blade from the stack into the razor upon movement of the slide in the opposite direction.

5. A device as in claim 2 wherein said blade supporting member comprises a blade magazine removably mounted within said housing.

10 4. A device as in claim 3 including a removable cover for that end of the housing opposite said opening whereby access may be had to said blade storage compartment for insertion and removal of said magazine.

15 5. An injector and blade removing device for an injector type razor, comprising a housing with a razor head attaching key by which the housing is operably associated with the razor head, magazine and blade disposal compartments in the housing and a slide movable longitudinally thereof, a blade magazine supported in the magazine compartment for limited upward movement in said compartment, an extractor operable with the slide for removing a blade from the razor upon movement of the slide in one direction, a camming element associated with said extractor and adapted to lift the magazine of unused blades on said movement of the slide and direct the used blade into the disposal compartment, and an injector member on the slide for discharging a blade from the magazine into the razor upon movement of the slide in the opposite direction, said camming element operating to depress the extractor and hold it in inoperable position during the blade injection cycle.

20 30 35 6. A device as in claim 5 with a lateral cam member on the razor head attaching key for moving the blade in the razor head into position for engagement by the extractor.
